UNITED STATES PATENT OFFICE.

IRVIN WILLIAMS, OF NELSON, AND WILLIAM H. GARLAND, OF KANSAS CITY,
MISSOURI; SAID GARLAND ASSIGNOR TO SAID WILLIAMS.

PERMUTATION-PADLOCK.

No. 853,569.

Specification of Letters Patent.

Patented May 14, 1907.

Application filed November 30, 1906. Serial No. 346,739.

To all whom it may concern:

Be it known that we, IRVIN WILLIAMS and WILLIAM H. GARLAND, citizens of the United States, residing, respectively, at Nelson and Kansas City, in the counties of Saline and Jackson and State of Missouri, have invented new and useful Permutation-Padlocks, of which the following is a specification.

10 This invention relates to permutation padlocks and its object is to provide a device of this character having simple locking mechanism therein which prevents the withdrawal of the shackle of the lock except by a predetermined combination, said combination being readily changeable without the provision of a key or other implement, provided the shackle is unlocked.

20 A still further object is to provide means whereby the actuation of the parts within the lock is prevented as long as a longitudinal pull is exerted upon the shackle.

25 With these and other objects in view the invention consists of certain novel features of construction and combinations of parts which will be hereinafter more fully described and pointed out in the claims.

30 In the accompanying drawings is shown the preferred form of the invention.

35 In said drawings: Figure 1 is an elevation of the padlock and showing the shackle unlocked and pulled outward from the casing; Fig. 2 is a central transverse section through the lock looking toward the shackle; Fig. 3 is a section on line $x-x$ Fig. 2; Fig. 4 is a view of the parts of the mechanism of the lock disconnected.

40 Referring to the figures by characters of reference, 1 is a ringlike casing having an interior annular flange 2 therein at the center thereof, said flange being interrupted by parallel passages 3 formed within the casing 1 and within extensions 4 upon the outer face of the casing. Annular recesses 5 are formed 45 in the edges of the ring 1 and constitute seats for the purpose hereinafter stated. A shackle 6 extends from the casing of the lock and one arm 7 of the shackle is longer than the other arm 8, said arm 7 being located within one of the passages 3 and being held against withdrawal therefrom by a stop pin 9 which extends through the end of said arm. The other arm 8 of the shackle is adapted to extend through the other passage 3 when the

lock is closed but, when the shackle is pulled outward to its greatest extent this short arm 8 thereof is drawn clear of the casing so that the shackle can be turned upon the arm 7. The two arms have recesses 10 formed in opposite portions thereof and in arcs concentric with the interior of the casing 1, and the inner walls of these recesses are formed with teeth or serrations 11. The recesses 10 are disposed so that when the arms of the shackle are pushed into the casing said recesses will receive rotatable tumblers. As shown in the drawings one of the tumblers consists of a disk 12 having an annular flange 13 at the periphery thereof, said flange being provided with teeth 14 upon its inner face. Two substantially semi-circular recesses 15 are formed in the flange 13 at distances apart equal to the distances between the passages 3. The disk 12 has its central portion struck inward or depressed as shown at 16. A circular opening 17 is formed within the central portion of this depression and disposed on the inner face of the depression adjacent the opening is a stop lug 18. The tumbler which has just been described is disposed within the casing 1 at one side of the flange 2 and is adapted to bear against said flange, and another oppositely disposed rotatable tumbler is located adjacent and bears upon the other side of the flange 2. This tumbler consists of a disk 19 having an annular flange 20 similar to the flange 13 and provided with teeth 21 upon its inner face. Two recesses 22, substantially semi-circular in form are provided in the flange 20 at a distance apart equal to the distance between the passages 3.

45 A central depression 23 is formed within the disk 19 and has a circular opening 24 at the center thereof. A dial plate in the form of a disk 25 rests upon the outer face of the tumbler 19 and has a suitable number of graduations adjacent the periphery thereof and a central depression 26 which is adapted to project into the depression 23 and has an angular opening 27 therein. Another disk 28 50 constituting a face plate bears upon the outer face of the tumbler 12 and has a central depression 29 which is adapted to project into the depression 16 and has a circular opening 30. The two disks 25 and 28 bear 55 upon the annular seats 5 hereinbefore referred to. Projections 31 are formed at desired intervals upon the dial 25. Projecting

through the angular opening 27 in said dial is an angular bolt 32 having a head 33 which is adapted to fit tightly within the depression 26. This bolt has a threaded recess 34 there- 5 in adapted to receive a screw 35 extending from a head 36 which is seated within the depression 29, and has a reduced cylindrical portion 27 which projects through the openings 30 and 17. Interposed between the two 10 tumblers is a ring 38 having an angular opening therein through which the bolt 32 projects, and a slip washer 39 is interposed between this ring and the depression 16 of tumbler 12 and has a lug 40 projecting therefrom 15 into the path of the lug 18 hereinbefore referred to. It will of course be understood that the tumbler 12 will rotate easily upon the reduced portion 37 of the head 36, whereas the remaining parts of the lock will be 20 tightly clamped between said reduced portion and the head 33 of bolt 32 although the tumbler 19 and the washer 39 will be capable of moving independently of the disk 25 and ring 38 if sufficient pressure is exerted there- 25 upon to overcome their frictional engagement.

An index mark 41 is located upon the casting 1 at any suitable point, preferably between the passages 3 and close to the periphery of the dial 25. When the recesses 22 and 15 register at the inner ends of the passages 3 it is of course possible to slide the arms of the shackle longitudinally through said recesses and into the position shown in Fig. 1. 30 When it is desired to lock the shackle the same is pushed into the casing, said inward movement being limited by a stop shoulder 42 therein formed upon the flange 2 and the recesses 10 will register with the flanges 13 and 20. By rotating the dial 25 in either direction by pressing upon one or more of the projections 31 the tumbler 19 will be rotated therewith as will also the washer 39 and lug 40, and this lug will come in contact with lug 45 18 and cause the tumbler 12 to also rotate. As soon as the recess in either of the tumblers moves out of register with the passages 3 the shackle becomes locked. The weight of the lock casing is sufficient to pull the 50 teeth of the tumblers downward into engagement with the teeth 11 on the shackle and it therefore becomes impossible to rotate the tumblers unless the shackle is pressed into the casing so as to disengage its teeth from 55 the tumblers. The combination necessary to open the lock consists of the graduations on the dial which register with the index 41 when recesses 15 and 22 register with the passages 3. Obviously by rotating the dial 60 25 to the left the lug 40 will swing against the lug 18 and rotate the tumbler 12 until the proper graduation registers with the index. The motion of the dial 25 is then reversed carrying only the tumbler 19 therewith and 65 when the proper graduation registers with

the index 41 the shackle can be withdrawn. While the shackle is unlocked in this manner the combination of the lock can be changed.

It is of course understood that the withdrawn shackle will prevent the tumblers from rotating but by exerting sufficient pressure upon the dial 25 the same can be rotated on the tumbler 19, the rotating ring 38 causing the washer 39 to also revolve. One complete rotation of the dial 25 is made to insure 70 the lug 40 coming into contact with lug 18. The rotation of the dial 25 is then continued until a desired graduation registers with index 41. The washer 39 will of course be held against this further rotation because of 75 the contact between the lugs 40 and 18. The number now registering with the index 41 is the number of the combination representing the tumbler 12. The dial 25 is then forced in an opposite direction and as the lug 18 is not 80 in the path thereof lug 40 rotates with the ring 38 and dial 25, although the tumbler 19 will be held stationary by the shackle 6. The dial 25 can be turned until any desired 85 graduation is brought in register with the index 41 and this graduation will be the number of the combination representing the tumbler 19. During this changing of combination the shackle will remain withdrawn so as to keep the tumblers from rotating and as 90 soon as the change has been effected the shackle can be pushed into the casing until the recesses 10 register with the flanges of the tumblers whereupon dial 25 can be rotated so as to carry the tumblers therewith and the 95 shackle will be securely locked in place.

It will be seen that any desired combination can be made and that, too, without introducing any particular tools or implements.

It is of course to be understood that more 100 than one washer or ring 38 can be employed and if desired the teeth 11, 14 and 21 may be dispensed with. However, these teeth are extremely desirable in-as-much as they prevent the rotation of the tumblers unless a 105 person has sufficient knowledge of the lock to draw the shackle and casing toward each other when it is desired to rotate the dial. The face plate 28 is preferably held against 110 rotation in any desired manner. A holding 115 pin 43 may be inserted into the casing 1 through a notch 44 formed within the periphery of said face plate.

The preferred form of the invention has been set forth in the foregoing description 120 but I do not limit myself thereto as I am aware that modifications may be made therein without departing from the spirit or sacrificing the advantages thereof, and I therefore reserve the right to make such changes as 125 fairly fall within the scope of the claims.

What is claimed is:

1. A permutation padlock comprising a casing, rotatable tumblers mounted therein, a projection upon one of said tumblers, a lug 130

- carrying element intermediate the tumblers, a dial, means for frictionally holding the lug carrying element and one of the tumblers normally against independent rotation and 5 for causing them to normally rotate with the dial, and a shackle movably mounted within the casing for engagement by the tumblers, the lug and projection being disposed in the same path.
- 10 2. A permutation lock comprising a casing, oppositely disposed rotatable tumblers therein, a shackle movable between the tumblers for engagement thereby, a lug upon one of the tumblers, a rotatable dial frictionally engaging the other tumbler, a slip 15 washer clamped between the tumblers and normally rotatable with the dial, and a projection upon the washer extending into the path of the lug to engage the same and actuate the tumbler.
- 20 3. A permutation lock comprising a casing having a passage therein, a shackle slidably mounted within said passage and having a recess, a rotatable tumbler mounted within 25 the casing, a flange upon the tumbler normally extending into the recess in the shackle, said flange having a recess adapted to register with the passage, and a dial frictionally engaging and normally rotatable 30 with the tumbler.
- 35 4. A permutation lock comprising a casing having a passage therein, a shackle slidably mounted within said passage and having a recess and teeth within the recess, a rotatable tumbler mounted within the casing and having 40 a flange normally extending into the recess in the shackle, said flange having a recess adapted to register with the passage, and a dial frictionally engaging and normally rotatable with the tumbler, said flange having teeth for engaging the teeth in the recess.
- 45 5. A permutation lock comprising a casing having a passage therein, a shackle longitudinally movable within the passage and having a recess and teeth within the recess, a 50 tumbler rotatably mounted within the casing and having an annular flange thereon normally seated within the recess in the shackle, said flange having a recess adapted 55 to register with the passage, there being teeth upon the flange for engaging the teeth in the recess, a graduated dial, a rotatable tumbler loosely mounted within the casing and normally projecting into the recess in the shackle, a lug upon said tumbler, fric-

tionally held means in the path of the lug and normally rotatable with the dial for engaging the lug to actuate the tumbler, and means for holding the dial in frictional engagement with the tumbler.

60

6. In a permutation lock the combination with a casing and a recessed shackle movably connected thereto; of a plurality of rotatable tumblers mounted therein for engaging the recessed portion of the shackle, said tumblers having recesses for registering with the shackle, a dial frictionally engaging one of the tumblers, a lug upon the other tumbler, said latter tumbler being loosely mounted, and frictionally held means interposed between the tumblers for engaging the lug to actuate the tumbler, said means being normally rotatable with the dial.

65

7. A permutation lock comprising a casing, of a recessed shackle projecting into and movably mounted within the casing, a rotatable tumbler loosely mounted within the casing and having a recessed flange, a lug upon said tumbler, a dial rotatably mounted upon the casing, a rotatable tumbler frictionally engaged by and normally movable with the dial, said tumbler having a recessed flange, said flanges adapted to normally engage the recessed portions of the shackle, and frictionally held means between the tumblers 85 and normally rotatable with the dial for engaging the lug to actuate the tumbler.

75

8. A permutation lock comprising a casing, a shackle movably mounted within and extending from the casing, a rotatable tumbler 90 loosely mounted within the casing and normally engaging the shackle, a rotatable dial, a rotatable tumbler within the casing and held in frictional engagement with the dial, and frictionally held means interposed between the tumblers and normally rotatable with the dial for actuating the loosely mounted tumbler.

95

In testimony that we claim the foregoing as our own, we have hereto affixed our signatures in the presence of two witnesses.
